(57) **CLAIM**

The ornamental design for a cargo management device, as shown and described.

DESCRIPTION

FIG. 1 is a front perspective view of the cargo management device in use;

FIG. 2 is a front view thereof;

FIG. 3 is a rear view thereof;

FIG. 4 is a side view thereof;

FIG. 5 is a side view thereof;

FIG. 6 is a top view thereof;

FIG. 7 is a bottom view thereof;

FIG. 8 is a rear perspective view thereof;

FIG. 9 is a front bottom perspective view thereof;

FIG. 10 is a rear bottom perspective view thereof;

FIG. 11 is a perspective view of the cargo management device in a folded position;

FIG. 12 is a front view thereof in a folded position;

FIG. 13 is a rear view thereof in a folded position;

FIG. 14 is a side view thereof in a folded position;

FIG. 15 is a side view thereof in a folded position;

FIG. 16 is a top view thereof in a folded position;

FIG. 17 is a bottom view thereof in a folded position;

FIG. 18 is a rear top perspective view thereof in a folded position;

FIG. 19 is a front bottom perspective view thereof in a folded position; and,

FIG. 20 is a rear bottom perspective view thereof in a folded position.

Portions of the cargo management device shown in broken lines in FIGS. 1-6, 8-16 and 18 form no part of the claimed design.

1 Claim, 12 Drawing Sheets
